MANIFOLDING MECHANISM FOR
TYPEWRITERS

James W. Fader, Dorchester, Mass.

Application April 5, 1937, Serial No. 134,930

8 Claims. (Cl. 282—29)

This invention relates to improvements in carbon carrier mechanism for manifolding a continuous series of forms on typewriters. Modern business methods require manifold copies of various instruments or forms, such as bills of lading, shipping orders, bills of account, specifications, etc. A continuous series of such forms have been produced having transverse perforations separating the adjacent forms, thereby enabling the typist to fill out the successive forms without removing the finished sheet and replacing a separate second sheet or sheets. Where such continuous strips are to be manifolded, suitable carbon sheets are interleaved between the superimposed sheets to be manifolded and carbon packs have heretofore been devised to enable a plurality of relatively short carbon sheets, approximately of the length of the form, to be employed and moved successively from one set of forms to the next after the typewritten manifolded form has been completed.

The present invention relates to an improved carbon pack and also to improved carbon carrying mechanism for accomplishing this purpose. The carbon pack of the present invention comprises broadly a plurality of carbon sheets of any desired number, the upper edges of which are secured respectively to strips of thin stiff material which project beyond the side edges of the sheet and are secured together and also have pivotally secured to the ends of the strips suitable means for connecting the carbon supporting strips to a follower and guide and which connecting means can be pivotally moved into parallelism with the strips, so that the carbon packs can be conveniently packaged and sold as a unit.

The invention also includes a novel form of movable guide and follower adapted to be detachably connected to the carbon pack by the connectors aforesaid, the follower being so constructed that it can be conveniently grasped by the operator and the carbon pack drawn lengthwise of the superimposed sheets and guided in parallelism therewith during such adjustment without displacing the position of the carbon sheets relatively to the side edges of the series of forms.

Another feature of the invention comprises the provision of a carbon carrier mechanism of the character specified which will enable the carbon sheets to be so adjusted with respect to successive forms that the type of the typewriter will not impinge upon the same area during the manifolding of the successive sheets, thereby in-

suring plain impressions of the type upon the several manifolded sheets.

These and other objects and features of the invention will more fully appear from the following description and the accompanying drawings and will be particularly pointed out in the claims.

A preferred embodiment of the invention is illustrated in the drawings, in which,

Fig. 1 is a plan view of a portion of a series of manifolding forms illustrating the position of the carbon sheets interleaved between the several sheets of forms and the mechanism which supports the carbon sheets and enables the same to be moved successively from one set of forms to another;

Fig. 2 is a vertical sectional view illustrating the series of forms interleaved with carbon sheets in the position when partially passed around the platen of a typewriting machine and showing the manner in which the carbon pack is secured to the follower and guide;

Fig. 3 is a view of the carbon pack illustrating in full lines the means for connecting the carbon pack to a suitable follower arranged in folded position in which the carbon pack can be packaged and sold and showing in dotted lines, partially broken away, the position of the connectors when secured to the follower and guide;

Fig. 4 is an underneath plan view of a preferred form of follower and guide;

Fig. 5 is a detail view of a carbon pack showing the manner in which the same is connected to the follower; and,

Fig. 6 is a detail view, mainly in vertical section, through the tubular member of the follower.

The carbon carrier mechanism is illustrated in Fig. 1 of the drawings as assembled upon the first of a series of forms 1, which usually are printed upon a continuous sheet of paper of any suitable length. Equally spaced lines of perforations 2 define the lengths of the several forms and provide means by which a typewritten form may be torn from the remainder of the sheet. As illustrated in Fig. 1 of the drawings three series of form sheets 3, 4, and 5, are illustrated with a carbon sheet 6 interleaved between the sheets 3 and 4, and another carbon sheet 7 interleaved between the sheets 4 and 5. The carbon sheets desirably are approximately the length of the form and each carbon sheet 6 and 7 is secured by adhesive or otherwise to a narrow strip of stiff thin material, such as fibreboard, Celluloid, or the like. As illustrated, the carbon sheet 6 is secured to a strip 8 and the carbon strip 7

is secured to a strip 9. The strips 8 and 9 are of sufficient length to extend such distance beyond the edges of the carbon strips as to permit a form sheet to be introduced between them with an original sheet lying over the outer carbon sheet 6 and another form sheet to lie beneath the carbon sheet 7 so that the forms may be typed in triplicate. Of course, any suitable number of carbon sheets may be similarly supported upon strips like 8 and 9 and superimposed in such manner that as many forms as may be desired can be manifolded simultaneously. The projecting end portions of the strips 8 and 9 are secured together by suitable pivotal connections, such as grommets 10, and the connectors 11 of the carbon carrier mechanism are pivotally mounted on the grommets or other means which connect the ends of the strips 8 and 9.

The connectors 11 desirably are formed of thin flexible stiff material, such as heavy paper or fibreboard, and means are provided for detachably connecting the upper ends of the connectors to a suitable follower and guide. In the preferred construction illustrated the upper ends of the connectors are provided with a binder 12 which embraces the upper edge of the connector and forms a thickened portion adapted to be engaged by holding means upon a tubular follower and guide.

The preferred form of follower and guide which is illustrated in Figs. 4, 5, and 6, comprises a tube 13 of a suitable size which has secured on each end an offset guide plate 14 which does not cover the end of the tube, but presents a flat face to engage and guide the side edges of the superimposed sheets. Each end of the tube 13 is provided with a slot 15 of a depth equal to the width of the connector 11 and the upper thickened end 12 of the connector 11 may be swung in such manner as to introduce the thickened end 12 into the tube with the thinner portion of the connector extending into the slot 15. If the tube is made of sufficiently rigid material the slot 15 may extend the full length of the tube.

The guiding plates 14 at the ends of the tube desirably are connected by a guide rod 16 spaced apart from the tube 13 a sufficient distance to permit the superimposed series of sheets to be manifolded to be passed through the space 17 between the rod 16 and the tube. The guide and follower mechanism thus formed will prevent separation and also lateral relative displacement of the sheets while permitting the follower to be slid freely longitudinally of the sheet.

Usually the forms are provided with blank portions 18 above the printing which will enable the superimposed sheets readily to be introduced into the typewriter and the platen 19 of the typewriter rotated in such manner as to draw the sheets into proper position for typing. Desirably the central portions of the lower ends of the carbon sheets 6 and 7 are cut away to provide recesses 20 of sufficient area to enable the superimposed form sheets to be grasped by the fingers and thumb of the operator without producing a carbon impression upon the sheets 4 and 5.

In the operation of the device the sheets 3, 4, and 5, to be typed are arranged so that the forms will register in superimposed relation. The sheets thus superimposed are first introduced through the space 17 between the rod 16 and the tube 13 of the follower and guide and drawn downwardly. The central sheet 4 is then introduced between the strips 8 and 9 which, by reason of their flexibility, can be readily separated for

such purpose and all of the sheets 3, 4, and 5, then drawn down until the carbon sheets cover the area of the form to be typed. The end portions of the sheets 18 are then introduced beneath the platen 19 of the typewriter and the platen rotated until the form is properly positioned relatively to the first line to be typed. The typewriter is then operated in the usual manner to type and manifold the first set of forms. After the first set of forms has been completed the platen 19 is rotated in a reverse direction by one hand of the operator and at the same time the tube 13 of the follower and guide is grasped by the other hand of the operator and raised. When the end portion 18 alone is clamped between the platen and the companion feeding member of the machine the lower ends of the carbon sheets will be freed and the follower and guide 13 may then be raised to slide the carbon sheets upwardly until properly positioned for manifolding the next form of the series. The platen 19 will then be rotated in a direction to feed the sheets forwardly and such rotation will be continued until the plain portion 18 of the next set of forms is clamped between the platen and its companion feeding member. The first set of forms may then be torn off along the perforated line 2 and the platen 19 again rotated in a feeding direction to position the first line to be typed upon the next form in proper position with relation to the type.

The connecting members 11 desirably are of material sufficiently stiff to maintain the follower and guide in properly spaced relation to the carbon pack.

One of the objects of the invention, as above stated, is to provide a carbon carrier mechanism comprising a follower and guide which may be packaged with any desirable number of carbon packs and used in the manner above described with each pack. Furthermore, the carbon packs may be packaged and sold separately from the follower and guide as each pack not only comprises the carbon sheets and the strips supporting them, but also the connectors which are pivotally mounted upon the strips of the carbon pack and are adapted to be folded into parallelism with the strips in such manner that several packs of carbon strips may be placed in a comparatively thin box or container.

It will be understood that the particular embodiment of the invention herein shown and described is of an illustrative character and that various changes in construction and arrangement of parts may be employed and that any desirable number of carbon sheets may be assembled for each carbon pack.

Having thus described the invention, what is claimed as new and desired to be secured by Letters Patent, is:

1. A carbon carrier mechanism for manifolding on a typewriter a superimposed series of like form sheets comprising a rigid guide adapted to extend transversely beneath said form sheets having means to engage the superimposed form sheets and means to hold the edges thereof in alignment, a carbon sheet carrier having means connected to the upper ends respectively of a plurality of carbon sheets and extending beyond the edges of said carbon sheets and united beyond said ends and holding said carbon sheets in parallelism and in separated relation to permit the form sheets to be slidably assembled in superimposed and interleaved relation to said carbon sheets, and flexible connecting strips secured to

the ends of said carrier having means detachably to engage said guide.

2. A carbon carrier mechanism for manifolding on a typewriter a superimposed series of like form sheets comprising a rigid metallic guide adapted to extend transversely beneath said form sheets having means to engage the superimposed form sheets and provided with guides to engage the edges of said form sheets and to maintain the same in alinement, said guide being provided at its ends with slotted tubular sockets, a carrier having means connected to the upper ends respectively of a plurality of carbon sheets and extending beyond the edges of said carbon sheets and united beyond said ends and, holding said carbon sheets in parallelism and in separated relation to permit the form sheets to be slidably assembled in superimposed and interleaved relation to said carbon sheets, and flexible connecting strips secured to the ends of said carrier having thickened free end portions adapted to be inserted in slots in said guide thereby detachably to connect said strips to said guide.

3. Carbon carrier mechanism for manifolding a continuous series of forms on a typewriter comprising a plurality of parallel carbon sheets, supporting strips of thin, stiff material secured to the upper edges of the respective sheets and projecting at their ends beyond the side edges of the sheets, means uniting the superimposed projecting ends of said strips, a connector pivotally mounted on each of said united ends, a guide for said continuous forms, and means detachably securing said connector to said guide.

35 4. Carbon carrier mechanism for manifolding a continuous series of forms on a typewriter comprising a plurality of parallel carbon sheets, supporting strips of thin, stiff material secured to the upper edges of the respective sheets and projecting at their ends beyond the side edges of the sheets, means uniting the superimposed projecting ends of said strips, a connector pivotally mounted on each of said united ends, and having a relatively thick end portion, a guide for said continuous forms comprising a tubular member having slots at its ends detachably to receive the thick end portions of the respective connectors.

5. Carbon carrier mechanism for manifolding a continuous series of forms on a typewriter comprising a plurality of parallel carbon sheets, supporting strips of thin, stiff material secured to the upper edges of the respective sheets and projecting at their ends beyond the side edges of the sheets, grommets uniting the respective superimposed projecting ends of said strips, a connector of

thin, relatively stiff, material pivotally mounted on each of said grommets and having a relatively thick free end portion, a guide for said continuous forms comprising a tubular member having slots at its ends detachably to receive the thick end portion of the respective connectors.

6. Carbon carrier mechanism for manifolding a continuous series of forms on a typewriter comprising a plurality of parallel carbon sheets, supporting strips of thin, stiff material secured to the upper edges of the respective sheets and projecting at their ends beyond the side edges of the sheets, grommets uniting the respective superimposed projecting ends of said strips, a connector of thin, relatively stiff, material pivotally mounted on each of said grommets and having a relatively thick free end portion, a guide for said continuous forms comprising a tubular member having slots at its ends detachably to receive the thick end portion of the respective connectors and provided at its ends with guiding members for the edges of said forms, and means connecting said edge guiding members extending in parallelism with said tubular member and spaced therefrom to permit the superimposed forms to pass therebetween.

7. As an article of manufacture a carbon pack for manifolding a continuous series of forms on a typewriter comprising a plurality of carbon sheets, supporting strips of thin, stiff material secured to the upper edges of the respective carbon sheets and projecting at their ends beyond the side edges of said carbon sheets, means uniting the superimposed projecting ends of said strips, and a connector of relatively thin stiff material mounted on each of the united ends of said strips and adapted to be swung into parallelism with and adjacent to said strips or at right angles thereto to project beyond the edge of said carbon sheets.

8. As an article of manufacture a carbon pack for manifolding a continuous series of forms on a typewriter comprising a plurality of carbon sheets, supporting strips of thin, stiff material secured to the upper edges of the respective sheets and projecting at their ends beyond the side edges of said sheets, and grommets uniting the respective superimposed projecting ends of said strips, and connectors of thin relatively stiff material pivotally mounted upon the respective grommets and adapted to be swung into parallelism with and adjacent to said strips or at right angles thereto to project beyond the edge of said carbon sheets.
